UNITED STATES PATENT OFFICE.

CHARLES J. WHIPPLE, OF CHICAGO, ILLINOIS, ASSIGNOR TO BARNHART BROTHERS & SPINDLER, OF SAME PLACE.

DESIGN FOR A FONT OF PRINTING-TYPE.

SPECIFICATION forming part of Design No. 20,253, dated November 4, 1890.

Application filed October 8, 1890. Serial No. 367,451. Term of patent 14 years.

To all whom it may concern:

Be it known that I, CHARLES J. WHIPPLE, a citizen of the United States, residing at Chicago, county of Cook, and State of Illinois, 5 have invented and produced a new and original Design for a Font of Printing-Type, which is fully set forth in the following specification, reference being had to the accompanying typographical impressions, forming a part thereof.

This design comprises upper and lower case letters, figures, dollar mark, character &, points, and an ornament. The letters are moderately extended, medium heavy-faced, 15 straight lines being uniform in body, curved lines generally tapering nearly to a point to make junction with other lines; but ends of all lines, whether straight or curved, which do not make junction with other lines are expanded, except in the case of terminals consisting of a heavy crescent swell.

The design is rendered grotesque and is distinctly characterized by the form of many of the heavy lines, which are bent rather than 25 curved, presenting a distorted appearance on account of the irregular or unconventional form. This characteristic is observable most prominently in lower-case f, g, h, j, k, m, p, q, s, t, v, w, x, and y, figures 4 and 7, and capitals 30 C, S, V, W, X, and Y. The bends thus noted are in no case angular, and in a few cases are flowing, but in most cases are abrupt without being sharp. Many capitals have one ele-

ment terminating in a spiral comprising a vertical crescent swell and a horizontal crescent swell merging together by an intermediate light line, such spiral being turned inward—that is, so as to be within the compass of the letter or between the stem of which it is the finish and the other stem of the letter 40 when the letter has two stems, being thus an interior as distinguished from an exterior flourish. This characteristic is found in capitals A, B, H, I, K, M, N, and X and character &. It is also found in lower-case x. 45

I claim—

The design for a font of printing-type herein shown and described, which is medium heavy-faced, having heavy lines generally merging in light connections with adjacent 50 lines, many heavy lines having grotesque or unconventional bends devoid of angles, several of the letters having one element terminating in a spiral flourish comprising a vertical and horizontal crescent swell merging in 55 a light connecting line and turned inward with respect to the remainder of the letter, substantially as set forth.

In testimony whereof I have hereunto set my hand, in the presence of two witnesses, at 60 Chicago, Illinois, this 6th day of October, 1890.

CHAS. J. WHIPPLE.
